IRONING MACHINE

Carridon G. Westwood, Chicago, Ill.

Application April 27, 1933. Serial No. 668,246

9 Claims. (Cl. 68—9)

The present invention relates to ironing machines, and more particularly to the type in which a single padded roller feeds the work over a stationary ironing surface.

5 An object of the present invention is to provide a means for transferring the goods to be ironed from the front of the machine to the back thereof and feeding such goods between the padded roller and the ironing surface at the back 10 of the machine so that the goods will be delivered in an ironed condition from between the padded roller and the ironing surface at the front of the machine, thereby enabling a single operator to take care of both feeding of goods to and 15 receiving them from between the padded roller and the ironing surface while standing at the front of the machine.

A more specific object of the present invention is to provide a simple and efficient means for feeding the goods to be ironed upwardly over the padded roller and between said padded roller and the ironing surface at the back of the machine so that the goods will be delivered in an ironed condition from between the padded roller 25 and the ironing surface at the front of the machine, thereby permitting a single operator to take care of both feed and delivery at the front or same side of the machine. By means of the present invention the necessity of a second operator at the back of the machine to feed the goods to be ironed between the padded roller and the ironing surface is avoided through the provision of a simple and efficient attachment which may be cheaply manufactured and readily installed 30 on existing ironing machines.

Other objects of the present invention will appear from the following description when considered in connection with the accompanying drawing, in which:

40 Figure 1 is a fragmentary front elevational view of an ironing machine equipped with a feeding device constructed in accordance with the present invention.

Figure 2 is a top plan view thereof.

45 Figure 3 is a side elevation looking toward the right of Figure 1.

Figure 4 is an enlarged fragmentary section on line 4—4 of Figure 1.

50 Figure 5 is a fragmentary view partly in elevation and partly in vertical section, showing the mounting means for the yieldable roller and the switching means associated therewith.

Figure 6 is a diagrammatic view showing the 55 manner of wiring the switching means of the

yieldable roller in the circuit of the driving motor for the padded roller.

A type of ironing machine now in general use comprises a stationary iron 5 in the form of an electrically or steam heated chest provided with 60 a concave ironing surface, and a single padded roller 6 cooperating with the concave surface of the iron 5 to effect ironing of goods fed between such roller and iron. In using a ironing machine of this type, an operator ordinarily stands at the 65 back of the machine, or to the left thereof as viewed in Figure 3, for feeding the goods to be ironed between the padded roller 6 and the iron 5, a second operator being necessary at the front 70 of the machine, or at the right thereof as viewed in Figure 3, to receive the ironed goods as they are delivered from between the roller 6 and the iron 5 at the latter side of the machine.

The primary object of the present invention is to provide means whereby a single operator 75 standing at the front of the machine may take care of both feeding and delivery of goods to and from the machine, thereby making the services of a second operator unnecessary.

A means for carrying out the present invention 80 includes a plurality of endless flexible belts 7 made of any suitable material and passing about pulleys or rollers 8, 9 and 10 at spaced points throughout the length of the padded roller 6, each belt 7 having a lower portion directed by 85 the rollers 8 and 9 so as to conform to and engage the convex upper surface of the padded roller 6. It will be noted that the belts 7 pass about the roller 8 at the front of the machine a material distance above the stationary iron 90 5 at this side of the machine so as to leave plenty of room for the operator to introduce the goods to be ironed between the belts 7 and the padded roller 6, and to receive the ironed goods from between the padded roller 6 and the stationary 95 iron 5. At the same time, the belts 7 pass about the roller 9 at the back of the machine in close proximity to the upwardly extending rear portion of the stationary iron 5, so that the goods fed between the belts 7 and padded roller 6 are 100 transferred to and effectively fed between the stationary iron 5 and padded roller 6 at the back 105 of the machine.

The rollers 8 and 9 are carried by shafts 11 and 12 suitably journaled in forwardly and rearwardly extending arms 13 and 14, respectively, of suitable supporting brackets 15 suitably rigidly secured as at 16 upon the frame 17 of the ironing machine at opposite ends of the padded roller 6. These arms 13 and 14 extend downwardly at 110

the front and back of padded roller 6 so as to position the rollers 8 and 9 below the top of padded roller 6, whereby the lower portion of each belt 7 is made to conform to the upper convex 5 surface of padded roller 6 as mentioned above and clearly shown in Figure 3. While frictional engagement of belts 7 with padded roller 6 may be relied upon for effecting driving of belts 7, such belts may be positively driven by the use of 10 suitable gearing (not shown) from the driven shaft of padded roller 6 to the shaft of any one or more of rollers 8, 9 and 10.

Projecting upwardly above the arms 13 and 14 are standards 18 rigid with brackets 15 and 16 slidably engaged by collars 19 supporting the ends of the shaft of upper roller 10, the standards 18 and roller 10 being disposed intermediate the rollers 8 and 9 as clearly shown in Figure 3. Helical compression springs 20 encircle the standards 18 between the sleeves 19 and brackets 15 so as to yieldingly elevate roller 10 and maintain the belts 7 under tension, thereby keeping the convex lower portions of belts 7 properly frictionally engaged with the periphery of padded roller 6. These elements serve as means for enabling the variation of the tension of the belts 7 and the friction between said belts and roller 6.

The standards 18 may project above the roller 10 to be connected at their upper ends by a transverse bar 21 having a plurality of pairs of depending fingers 22 engaging the periphery of roller 10 at opposite sides of the belts 7 to properly guide and keep the belts 7 separated.

In operation, the goods to be ironed are fed between the belts 7 and the upper portion of padded roller 6 at the right hand side of the machine as viewed in Figure 3, being carried upwardly over said padded roller 6 and then downwardly between the rear portion of stationary iron 5 and padded roller 6. The iron 5 and roller 6 then cooperate to effect ironing of the goods, feeding the same forwardly and delivering them in an ironed condition at the front or right hand side of the machine as viewed in Figure 3. It will thus be seen that the goods may be fed between the iron 5 and roller 6 and received therefrom by a single operator maintaining a position at one side of the machine, thus rendering the services of a second operator unnecessary.

As shown clearly in Figure 5, the roller 8 is pressed by springs 25 toward the padded roll 6 so as to be yieldably positioned away from the latter, and means is provided to automatically throw out of operation the motor for driving the roll 6 when the roller 8 is forced a predetermined excessive distance away from roll 6, such as will occur should the operator's hand be caught between roll 6 and roller 8 when feeding the material to be ironed between the belts 7 and roll 6. By the use of this safety device, injury to the operator may be prevented. As shown, the ends of the shaft 11 of roller 8 are movable in elongated slots 26 of arms 13, and the springs 25 bear against the ends of shaft 11 to yieldingly urge the roller 8 toward roll 6. Any suitable switching means may be utilized to stop the driving motor 27 of roll 6 (Figure 6) when roller 8 is forced a sufficient distance away from roll 6. As shown, a switch may be associated with each arm 13 at each end of shaft 11, each switch including a plunger 28 bearing against shaft 11 and carrying a movable contact 29 normally bridging stationary contacts 30. The switches are wired in series in the circuit of motor 27.

as shown in Figure 6 so that such circuit will be broken if either end of roller 8 is forced away from roll 6 a sufficient distance to disengage the movable contact 29 of one of the switches from the associated stationary contacts 30. 80
Slight yielding of roller 8, such as caused by the insertion of goods to be ironed between belts 7 and roll 6 will not effect sufficient movement of contacts 29 to disengage them from contacts 30, but the insertion of a thicker object, such as the operator's hand, will do so. The usual manually operable switch 31 is provided to manually throw the motor 27 into and out of operation. 85

From the foregoing description, it will be seen that the present invention may be readily applied to existing ironing machines at a small cost and will efficiently function in the manner contemplated. Minor changes are contemplated within the scope of the invention as claimed. 90

What I claim as new is:

1. The combination with an ironing machine provided with a stationary iron having a concaved ironing surface and a padded roller co-operating with said concaved surface, of means mounted on the frame of the machine and including movable feeding elements cooperating with an exposed portion of said padded roller for feeding goods to be ironed on said padded roller at one side of the machine and then between the latter and the stationary iron at the opposite side of the machine. 100 105

opposite side of the machine.

2. The combination with an iron having a concaved surface, and a padded roller arranged above the iron and cooperating with said concaved surface, of a plurality of endless belts arranged above said padded roller and each having a lower portion conforming to and engaging the convex upper surface of said roller for cooperating with the latter to transfer goods to be ironed from the front of the padded roller to the back thereof and to feed the goods between the padded roller and the iron at the back of said roller.

3. The combination with an ironing machine provided with a stationary iron having a concaved ironing surface and a padded roller arranged above the iron and cooperating with said concaved surface, of brackets rigidly mounted on the frame of the machine at opposite ends of said roller and having forwardly and rearwardly downwardly curving arms, rollers journaled in the forward and rear ends of said arms respectively in spaced relation above the front portion of the stationary iron and in close proximity to the rear portion of the stationary iron, and a plurality of endless belts passing around the last-named rollers at spaced points throughout the length of the padded roller and each having a lower portion conforming to and engaging the convex upper surface of the padded roller to cooperate with the latter for transferring goods to be ironed from the front of the padded roller to the back thereof and for feeding the goods between the stationary iron and the padded roller at the back of the latter. 140

4. The combination with an ironing machine provided with a stationary iron having a concaved ironing surface and a padded roller arranged above the iron and cooperating with said concaved surface, of brackets rigidly mounted on the frame of the machine at opposite ends of said roller and having forwardly and rearwardly downwardly curving arms, rollers journaled in the forward and rear ends of said arms respectively in spaced relation above the front portion 145

- of the stationary iron and in close proximity to the rear portion of the stationary iron, a plurality of endless belts passing around the last-named rollers at spaced points throughout the 5 length of the padded roller and each having a lower portion conforming to and engaging the convex upper surface of the padded roller to cooperate with the latter for transferring goods to be ironed from the front of the padded roller 10 to the back thereof and for feeding the goods between the stationary iron and the padded roller at the back of the latter, standards rigid with and rising from said brackets, a further roller having a supporting shaft slidably engaged with 15 said standards for vertical movement relative to the latter, and yieldable means associated with said standards for constantly urging the latter roller upwardly to maintain the belts under tension with the convex lower portions of said belts 20 frictionally engaged with the upper surface of the padded roller.
5. The combination with an ironing machine provided with a stationary iron having a concaved ironing surface and a padded roller arranged above the iron and cooperating with said concaved surface, of brackets rigidly mounted on the frame of the machine at opposite ends of said roller and having forwardly and rearwardly downwardly curving arms, rollers journaled in 30 the forward and rear ends of said arms respectively in spaced relation above the front portion of the stationary iron and in close proximity to the rear portion of the stationary iron, a plurality of endless belts passing around the last-named 35 rollers at spaced points throughout the length of the padded roller and each having a lower portion conforming to and engaging the convex upper surface of the padded roller to cooperate with the latter for transferring goods to be ironed from 40 the front of the padded roller to the back thereof and for feeding the goods between the stationary 45 iron and the padded roller at the back of the latter, a motor for driving said padded roller, the roller journaled in the forward ends of said arms being yieldable away from said padded roller, and switch means operated by said yieldable roller for automatically throwing said motor out of operation upon excessive movement of said yieldable roller away from said padded roller. 50
6. An ironing machine comprising a moving padded roller, a stationary iron cooperating with said roller, said iron having a concaved ironing surface adjacent part of the surface of said roller, and feeding means mounted opposite said iron and cooperating with the surface of said roller for feeding goods to be ironed across the surface of said roller opposite said iron and for then guiding said goods between said iron and said roller. 55
7. The structure of claim 6 wherein said feeding means comprises at least one endless band yieldingly engaging the surface of said roller. 60
8. An ironing machine comprising a moving padded roller, a stationary iron cooperating with said roller, said iron having a concaved ironing surface adjacent part of the surface of said roller, an endless feeding band mounted opposite said iron yieldingly and frictionally engaging the surface of said roller, and means for enabling variation of the tension of said band. 65
9. An ironing machine comprising a moving padded roller, a stationary iron cooperating with said roller, said iron having a concaved ironing surface adjacent part of the surface of said roller, an endless feeding band mounted opposite said iron yieldingly and frictionally engaging the surface of said roller, and means for automatically stopping said moving roller upon a predetermined separation between said feeding band and said roller. 70
